UNITED STATES PATENT OFFICE.

GEORGE BRANDT, OF NEW YORK, N. Y., ASSIGNOR TO BENRUS WATCH CASE COMPANY,
OF NEW YORK, N. Y., A CORPORATION OF NEW YORK.

FLEXIBLE CHAIN.

Application filed August 21, 1928. Serial No. 301,024.

This invention relates to a flexible chain construction and relates more particularly to an improved flexible chain adapted to be used as a bracelet or other similar article of jewelry.

The prime desideratum of my present invention centers about the provision of a flexible chain or bracelet embodying an organization of units and linkage members which may be constructed and assembled in a rapid and economical manner by automatic machinery without the necessity of employing soldering, welding, or other similar time consuming operations.

15 A further prime object of the invention relates to the provision of a chain structure suitably adapted for use as a watch bracelet made up of inexpensive structural linkage members and units capable of being readily assembled into a strong and durable chain formation which, due to the substantial savings in labor and material costs involved, yields an inexpensive bracelet chain capable of being marketed at a low cost to the consumer.

20 A still further prime object of the invention is directed to the provision of a chain formation which possesses the characteristics of attractive neatness, symmetry, strength, durability, flexibility in a number of directions, and uniformity of appearance.

25 To the accomplishment of the foregoing and such other objects as will hereinafter appear, my invention consists in the elements and their relation one to the other, as hereinafter more particularly described and sought to be defined in the claims; reference being had to the accompanying drawings which show the preferred embodiments of

30 my invention, and in which:

Fig. 1 is a perspective view of the chain construction showing its use as a watch bracelet;

35 Fig. 2 is a fragmentary view thereof shown on an enlarged scale with parts shown in section;

Fig. 3 is a view taken in cross-section in the plane of the line 3-3, Fig. 2;

40 Fig. 4 is a perspective view of the essential elements used in making up the chain with the parts thereof shown detached prior to assembly;

45 Fig. 5 is a cross-sectional view similar to Fig. 3 but of a modification thereof;

50 Referring now more in detail to the draw-

ings, having reference first to Figs. 1 to 3 thereof wherein I show one form of construction that my invention may take, the flexible chain of the invention is shown to comprise a plurality or series of relatively elongated units *a-a* arranged in close transverse formation and hollow at at least one of their ends and preferably at both of their ends, a plurality or series of linkage members *b-b* connecting the units *a* in chain formation, said linkage members being received by the hollow ends of the units *a* and mating means generally designated as *c* formed integrally with the units and the linkage members for interlockingly assembling the units and members together into a chain construction.

Preferably the elongated units *a-a* comprise relatively elongated tubular elements made of metal open at their opposite ends 10 and 11, the said tubular elements or units desirably being rectangular in cross-sectional dimensions, as best shown in Fig. 4 of the drawings. The tubular units *a-a* are arranged in close formation with their side walls in substantially abutting relation, as clearly shown in the drawings, the construction and arrangement being such that the front and rear faces of the chain present a substantially continuous appearance. The tubular elements *a* may be made by cutting standard tubing into the desired lengths.

The linkage members *b-b* each comprises a U-shaped element having a transverse connecting portion 12 and two leg portions 13 and 14 depending therefrom, the said leg portions 13 and 14 being received by the open ends of the tubular units *a-a* at at least one side of the chain formation and preferably by both sides thereof, as shown in the exemplification of the invention disclosed in the drawings. These U-shaped linkage members *b-b* are preferably blanked out of sheet metal to produce the configuration best shown in Figs. 2 and 4 of the drawings. To produce the desired flexibility of the chain construction, the width of each leg 13-14 is slightly less than one-half the width of the receiving openings of the tubes *a-a* and the width of the space 15 between said legs is slightly greater than the combined thicknesses of the abutting side walls of the tubes *a-a*, all as clearly shown in Fig. 2 of the drawings. The thickness of the sheet metal out of which the linkage blanks are made is also slightly less than the depth of the open-

ings of the tubes *a—a* so that small clearances are provided, as clearly shown in Fig. 3 of the drawings. With this recited construction, the opposite legs of a linkage member are received by adjacent tubular units and adjacent legs of contiguously positioned linkage members are received by the same tubular unit, and the assembly of these parts is such that the legs of the linkage members substantially fill the tubular openings with clearances provided, however, sufficient to produce the desired flexibility. It will also be noted that the transverse connecting portions 12 of the linkage members define substantially continuous and neat edges for both sides of the chain formation, smooth and continuous chain surfaces and edges being thus provided.

The interlocking means *c* for the hollow or tubular units and linkage members are formed integrally with the tubular units and linkage members so that no additional securing elements are needed and so that these units and members may be readily assembled and without the use of soldering, welding or other time consuming operations. This interlocking means is furthermore so arranged and constructed as to minimize interference with the flexibility of the chain structure and is so positioned as to prevent any of the usage strains from being applied to the interlocking means, the result in construction being characterized thereby by strength, durability and optimum flexibility. One of the preferred ways of constructing this interlocking means is shown in Figs. 1 to 3 of the drawings. In this form of the invention the legs 13 and 14 of the linkage members are blanked out to provide oppositely positioned recesses 16 and 17 of substantially semi-square dimensions, the arrangement being such that contiguous recesses of the adjacent legs of adjacent linkage members define substantially square openings, as clearly shown in Fig. 2 of the drawings. The tubular members *a* in turn are provided with stamped out teeth 18—18 which are stamped up inwardly into mating relation with the square openings defined by adjacent recesses 16 and 17, as clearly shown in Figs. 2 and 3 of the drawings. In the form of the invention shown in Figs. 1 to 4, the tubes *a* are first assembled with the linkage members *b* in the manner shown in Fig. 4 of the drawings, and after being assembled the burrs or teeth 18—18 are produced by means of a suitable die, the linkage members *b* serving in this operation as filling means for the tubular elements. It will be noted that the teeth 18 are produced on that side of the chain which forms the inside of the bracelet and are thus unexposed during normal use of the bracelet chain.

With the construction thus far described, it will therefore be seen that the linkage members and the tubular units may be read-

ily made from inexpensive stock and quickly assembled by automatic machinery in a very facile manner and by quantity production methods. It will also be seen that the elements composing the chain are locked together in assembled relation, the strains incident to use being applied at regions other than at the interlocking means. It will further be seen that the chain may be readily mended when desired by forcibly withdrawing the linkage members and reinserting the same in the desired locations.

In the modification of the invention shown in Fig. 5 of the drawings, the teeth 18' are struck out in directions opposite to those shown in Figs. 1 to 3 of the drawings. Otherwise the structure of Fig. 5 is the same as that heretofore described and the parts are designated by similar and primed reference characters. In this modification of Fig. 5 of the drawings, the linkage members *b'* are positively locked in position against withdrawal. In this form of construction, however, the teeth or burrs 18' may be formed prior to assembly of the chain and the linkage members may be snapped into position in the assembling operation, claimed in a divisional co-pending application.

To complete the chain formation when used as a bracelet, an adjustable strap tightening buckle 20 of any approved construction may be used and the end units of the chain may be provided with means to which a wrist watch, such as 21, may be attached. One of such end units is shown in Fig. 2 of the drawings and may comprise a tubular element 22 for receiving a fixture of the wrist watch, the said tubular element being provided with an integral tube section 23 of a width substantially one-half that of the tube *a*, the said tubular section 23 being provided with the struck in teeth 24—24 similar to those described for Figs. 6 and 7 of the drawings, these teeth cooperating with a special linkage member 25, one side of which is constructed after the manner of the linkage members shown in Figs. 1 to 4 of the drawings and the other side of which is constructed after the manner of the linkage members shown in Figs. 6 and 7 of the drawings.

The manner of making and assembling the chain formation of my present invention and the many advantages thereof in the course of manufacture and use will in the main be fully apparent from the above detailed description thereof. It will further be apparent that while I have shown and described my invention in the preferred forms, many changes and modifications may be made in the structure disclosed without departing from the spirit of the invention, defined in the following claims.

What I claim is:

1. A flexible chain comprising tubular units, linkage members connecting the tu-

- 5 bular units, said linkage members comprising sheet blanks each having a transverse connecting portion and depending leg portions, the leg portions being received by the tubular units and inserted therein at the opposite ends thereof, and means formed from a single face of the tubular units for interlocking the linkage members and the tubular units, the transverse connecting portions of the linkage members defining substantially continuous edges for the chain formation.
- 10 2. A flexible chain comprising tubular units, linkage members connecting the tubular units, said linkage members comprising sheet blanks each having a transverse connecting portion and depending leg portions, the leg portions being received by the tubular units and inserted therein at at least one end thereof, said tubular units being provided on one face with stamped out portions interlocking with the leg portions of the linkage members.
- 15 3. A flexible chain comprising tubular units arranged in close and substantially continuous formation, U-shaped linkage members connecting the tubular units at their opposite ends, the legs of a linkage member being received by adjacent tubular units and adjacent legs of contiguous linkage members being received by the same tubular unit, and means interlocking the linkage members and tubular units, said interlocking means being formed from a single face of said tubular units, and said linkage members defining substantially continuous edges for the opposite sides of the chain.
- 20 4. A flexible chain comprising tubular units arranged in close formation, U-shaped linkage members connecting the tubular units, the legs of a linkage member being received by adjacent tubular units and adjacent legs of contiguous linkage members being received by the same tubular unit, tooth elements stamped out of a single face of the tubular units, and means on the legs of said linkage members interlocking with said tooth elements.
- 25 5. A flexible chain comprising tubular units arranged in close formation, U-shaped linkage members connecting the tubular units, the legs of a linkage member being received by adjacent tubular units and adjacent legs of contiguous linkage members being received by the same tubular unit, the legs of the members being provided with recesses, recesses of adjacent legs defining an enclosed opening, and detent indentations struck out from said tubular units engaged in and inter-locking with said openings.
- 30 6. A flexible chain comprising tubular units arranged in close formation, U-shaped linkage members connecting the tubular units, the legs of a linkage member being received by adjacent tubular units and adjacent legs of contiguous linkage members being received by the same tubular unit, recesses on the legs of said linkage members, recesses on the legs of said linkage members each of which engages the recesses in the adjacent legs of contiguous linkage members for inter-locking said linkage members and said tubular units.
- 35 7. A flexible chain comprising tubular units which are substantially rectangular in cross-section and arranged in close formation, U-shaped linkage members connecting the tubular units, the legs of the linkage members being received by adjacent tubular units and adjacent legs of contiguous linkage members being received by the same tubular unit, recesses on the legs of said linkage members and indentations stamped in the tubular units each of which engages the recesses in the adjacent legs of contiguous linkage members for inter-locking said linkage members and said tubular units.
- 40 8. A flexible chain comprising tubular units which are substantially rectangular in cross-section and arranged in close formation, U-shaped linkage members connecting the tubular units, the legs of a linkage member being received by adjacent tubular units and adjacent legs of contiguous linkage members being received by the same tubular unit, the legs of the members being provided with recesses, recesses of adjacent legs defining an enclosed opening, and detent indentations struck out from said tubular units engaged in and inter-locking with said openings.
- 45 9. A flexible chain comprising tubular units arranged in close formation, U-shaped linkage members inserted in the tubular units along at least one side of the chain formation, the legs of linkage members being received by adjacent tubular units and adjacent legs of contiguous linkage members being received by the same tubular unit, a common detent indentation stamped out of each tubular unit, and means on the adjacent legs of said linkage members within each of said units for inter-locking with the common detent indentation thereof.
- 50 10. A flexible chain comprising tubular units, linkage members connecting the tubular units, said linkage members comprising sheet blanks each having a transverse connecting portion and depending leg portions, the leg portions being received by the tubular units and inserted therein at at least one end thereof, said tubular units being provided with stamped out portions commonly interlocking with both of the leg portions of the adjacent linkage members inserted therein.
- 55 Signed at New York, in the county of New York and State of New York this 10 day of August, A. D. 1928.
- 60 6. A flexible chain comprising tubular units arranged in close formation, U-shaped linkage members connecting the tubular units, the legs of the linkage members being received by adjacent tubular units and ad-
